UNITED STATES PATENT OFFICE

ALFRED A. RODGERS, OF LOS ANGELES, CALIFORNIA, ASSIGNOR TO SCULLY BROS. INC., OF LOS ANGELES, CALIFORNIA, A CORPORATION OF CALIFORNIA

DESIGN FOR A GOLF CLUB BOOT

Application filed April 16, 1931. Serial No. 39,507. Term of patent 7 years.

To all whom it may concern:

Be it known that I, ALFRED A. RODGERS, a citizen of the United States, residing at Los Angeles, in the county of Los Angeles and State of California, have invented a new, original, and ornamental Design for a Golf Club Boot, of which the following is a specification, reference being had to the accompanying drawings, forming part thereof.

I claim:

The ornamental design for a golf club boot, as shown.

Signed at Los Angeles, in the county of Los Angeles, State of California, this 9th day of April, 1931.

ALFRED A. RODGERS.
